UNITED STATES PATENT OFFICE.

BLUFORD W. BROCKETT, OF CLEVELAND, OHIO, ASSIGNOR TO THE AMERICAN LAUNDRY MACHINERY COMPANY, OF CINCINNATI, OHIO, A CORPORATION OF OHIO.

WORK-SHIRT PRESS.

1,387,099.

Specification of Letters Patent.

Patented Aug. 9, 1921.

Application filed September 9, 1916. Serial No. 119,290.

To all whom it may concern:

Be it known that I, BLUFORD W. BROCKETT, citizen of the United States, residing at Cleveland, in the county of Cuyahoga and State of Ohio, have invented certain new and useful Improvements in Work-Shirt Presses, of which the following is a specification.

This invention relates to presses, and more particularly to what are known as work-shirt presses.

Work-shirts are provided with attached soft collars and when manufactured are folded up and pressed down flat for packing into bundles or boxes. It is desirable to press the shirt in a manner to improve its folded appearance and thereby enhance its value and selling qualities, but considerable difficulty has been experienced in arranging the collar and holding it in symmetrical flat form while pressing the shirt, due to the cylindrical form of neckband and the necessity of stretching and crushing all of the parts, but more especially the collar, into an unnatural position down flat. The parts of the shirt have, therefore been liable to become disarranged during the pressing operation or while moving the shirt up to the pressing position.

The invention has for its object to provide improved apparatus which enables the operator to arrange the shirt collar, neckband and adjacent parts in the most desirable position and so hold them until finally pressed, thereby producing an attractive appearance and the best pressing results; and which apparatus can be operated by unskilled labor, can be applied to various types of pressing machines, and is of simple form and not liable to get out of order.

Further objects of the invention are in part obvious and in part will appear more in detail hereinafter.

The invention comprises the apparatus hereinafter described and claimed.

In the drawings, Figure 1 represents a front elevation of one suitable form of pressing machine with my invention applied thereto, one of the pressing members being omitted; Fig. 2 is a plan view, on a larger scale, of a lower pressing head with a shirt thereon in position to be pressed; Fig. 3 is an end view thereof; Fig. 4 is a side eleva-

tion thereof; Fig. 5 is a detail view, corresponding to Fig. 4, and illustrating the motion of the holding plate; and Fig. 6 is a detail view showing a portion of a shirt with modified form of pressing plate or form applied thereto.

The pressing machine to which the invention is applied may be of any suitable form so long as it embodies the essential relatively movable heated pressing members or bucks between which the shirt is pressed. During the pressing operation said pressing members are advanced and retracted toward and from each other, with the shirt lying on the lower pressing member. For this motion either or both of said pressing members may be movable. One of said members may also have lateral motion relative to the other to move it into and out of co-operating relation therewith.

In the drawings, the invention is shown applied to a pressing machine in which the upper pressing member is stationary and co-operates with two lower pressing members brought successively into co-operating relation with the upper pressing member, thereby enabling the operator to apply to and arrange a shirt upon one pressing member while a previously arranged shirt is being pressed by the other pressing member. The machine shown comprises a suitable frame 1 having a head 2 which supports the rigid immovable upper pressing member 3. Said frame is provided at one side with a vertical shaft or post 4 on which is mounted a frame 5 turning about the vertical axis of said post and comprising two oppositely disposed arms 6 whose ends are formed to provide sleeves 7 in which are located depending posts 8 slidable vertically in said sleeves and at their upper ends attached to the lower pressing members 9, the one only of which is shown. Said two lower pressing members are of identical form and are connected to the frame 5 and operate in the same manner, so that a description of one will suffice for both.

Directly below the upper pressing member 3 the base 10 of the main frame is provided with a vertically slidable plunger 11. By rotating the frame 5 the two lower pressing members may be brought successively into position over said plunger, as shown in

Fig. 1, and by elevating the plunger its upper end enters the sleeve 7, locks the frame 5 against lateral movement, and moves the lower pressing member upwardly 5 into engagement with the upper pressing member for pressing the shirt. The plunger 11 may be operated in any suitable manner, the drawings showing for this purpose a pivoted lever 12, one of whose arms engages 10 the bottom of the plunger 11, and whose other arm is connected by a rod 13 to a cross head 14 sliding on the vertical frame posts 15 and rigidly attached to the rod 16 of a piston 17 sliding in the cylinder 18, to which fluid pressure, such as compressed air or steam, may be admitted 15 through a conduit 19. The flow of pressure to said cylinder, and its exhaust therefrom are controlled by a suitable valve (not 20 shown) connected to the pipe 19, as will be readily understood.

The shirt to be pressed, indicated at A, is folded in the usual form and laid upon the lower pressing member, as shown in Fig. 2. 25 The appearance of the shirt and its desirability in trade are greatly enhanced, if the collar and the yoke and other parts of the shirt adjacent thereto can be pressed down flat without wrinkles or folds and symmetrically disposed with reference to the body of 30 the shirt. For example, the folds 20 in the portions of the yoke at the sides of the collar, the seam 21 between the back of the neck band and yoke, and the fold 22 between the 35 back of the neck band and collar should preferably extend in lines truly transverse to the longitudinally extending button-hole strip 23, while the exposed front portions 24 of the collar must lie flat without wrinkles 40 and symmetrically disposed on either side of the button-hole strip. This desirable arrangement is secured by the use of a pressing plate or form 25, which may be made of sheet metal or other stiff material, and which 45 is laid upon the shirt while in position on the lower pressing member. The pressing form is of peculiar shape, one of its ends being cut out to form a V-shaped recess with substantially straight edges 26 inclined to 50 each other, on either side of which are smaller V-shaped recesses or notches 27, forming outwardly extending V-shaped points or projections 28. The rest of the 55 form is a plain flat sheet large enough to completely cover the entire shirt. The operator lays the shirt upon the lower pressing member and slips the points 28 of the form beneath the side portions of the collar, stretching the collar parts to approximately 60 correct position and pushing the form plate up toward the collar until the edges 26 of the large V-shaped slot are fully seated beneath the collar, as shown in Fig. 2. These substantially straight edges permit the side 65 collar portions to be stretched or pulled

down flat without wrinkles, with the folds 29 between said collar portions and the neck band extending in substantially straight diverging lines. The opening in the collar, through which the seam is exposed is therefore substantially an equilateral triangle. The inner edges of the notches 27 also form outwardly inclined folds 30 in the collar on either side of the shirt. 70

The shirt, arranged on the lower pressing member as described, may be immediately subjected to the pressing operation by moving the lower pressing member into position beneath its coöperating upper pressing member. The exposed side portions of the collar, 75 however, are limp and usually will not lie down flat. Moreover, the operator must remove her hands from said collar portions to allow the pressing members to be brought into pressing relation with each other and 80 the collar portions may become disarranged while moving the two pressing members into pressing relation. Suitable means is preferably therefore provided for holding the exposed parts of the collar, and in fact all 85 of the parts of the shirt adjacent the collar, 90 in their previously arranged positions, so that they will be pressed in the manner intended by the operator. This means comprises a holding plate, indicated at 31, which 95 is movably connected to the lower pressing member and is adapted to be moved to either of two positions, in one of which it is at one 100 side of the lower pressing member, allowing free access by the operator to the shirt, 105 and in the other of which it lies over the shirt and is yieldingly pressed down against the same to retain it in properly arranged position. In this latter position the holding plate preferably also has a sliding movement along the shirt, in a plane parallel with the face of the pressing member, first engaging the shirt in a manner to only cover a portion of the collar leaving the lower ends thereof exposed, as in dotted lines, Fig. 2, so 110 that the operator can gradually withdraw her fingers from the collar as said plate slides down over the same to completely cover it, as indicated by the full and dot and dash lines, Fig. 2. 115

The holding plate may be arranged in any suitable manner to secure the two positions and the motion described. As shown in the drawings it is attached at one edge to two short arms 32 pivoted at 33 upon a 120 U-shaped frame 34 whose arms are rigidly connected, as by set screws 35, to turn with shaft members 36 rotatable in two supports 37 attached to brackets 38 mounted on the collar end of the lower pressing member. Said supports are provided with elongated vertical slots 39 through which the clamping bolts 40 are threaded into said brackets, so that the supports may be adjusted vertically relative to the lower pressing member 125 130

- to compensate for the various thicknesses of the padding 41 on said member and to permit the plate 31 to be brought down into close fitting position upon the shirt. In 5 front of the pivot 33 the cross bar 42 of the U-shaped frame has an upper flat face 43, and in the inoperative position of the holding plate, shown in dotted lines in Figs. 3 and 4, said plate is held against said flat face 10 by a tension spring 44 connected at one end to said plate and at its opposite end to a fixed support 45. In said inoperative position, also, the spring is at the left of the pivot shafts 36, as shown in Fig. 4, so that 15 said spring tends to hold the plate in the inoperative position. Furthermore, one or both of the arms of the U-shaped frame 34 are provided with stop pins 46 which engage the fixed supports 37 and limit the outward 20 movement of said plate.
- One of the shaft members 36 is provided with an operating handle 47, which extends upwardly in the inoperative position of the plate, but which may be turned down toward 25 the position shown in full lines, Fig. 4, thereby switching the spring 44 to a position at the right of the pivot shaft members 36 where said spring tends to press the holding plate yieldingly downward upon the shirt. 30 During the first movement of the holding plate toward the shirt it is held in contact with the flat outer face 43 of the U-shaped frame, and first engages the shirt in the position shown in dotted lines Fig. 2 and in 35 full lines Fig. 5, leaving the free ends of the collar exposed. The operator therefore can hold her fingers on the said collar ends while pulling the holding plate down to position. The handle 47 is then advanced still farther 40 until the pins 46 engage stops 48. This movement causes the frame 42 to move in a clockwise direction, Fig. 5, which advances the plate with a sliding motion over the shirt by engagement therewith to the position 45 shown in full and dot and dash lines Fig. 2, and in dotted lines Fig. 5. During this motion the flat face 43 of the U-shaped frame moves away from the plate, to the position shown in Fig. 4 and, as said plate moves over 50 the shirt, the operator gradually withdraws her fingers from the collar so that when said plate reaches its final position, the collar is held down in flat form and without wrinkles as previously arranged by the operator. 55 The lower pressing member, with the shirt thereon, is then moved laterally to pressing position beneath the upper pressing member, as shown in Fig. 1, and is advanced with pressure into pressing relation with the upper member for pressing the shirt.
- In the form of apparatus so far described, the pressing plate or form has a plain V-shaped central notch or recess to fit the collar, and the top button 49 between the collar ends is hidden under the plate. Fig. 6

shows a modified form of pressing plate or form in which the V-shaped central notch terminates in a short narrow recess or slot 50 with parallel side edges. This plate is pushed up into position under the collar, as 70 before, but with adjacent portions of the collar entering and held in the narrow recess or slot 50, said collar portions being, therefore, drawn closely together so as to cover and conceal the top button, which may also 75 enter the slot but preferably lies wholly beneath the pressing plate or form. This plate is, therefore, adapted for pressing shirts where the manufacturer desires to conceal the top button, as he frequently does. 80 It may be used in connection with a movable holding plate of the same form before described and in the same manner.

Both the upper and lower pressing members are preferably heated by steam or other 85 heating fluid introduced into hollow chambers therein, or in any other manner, as is usual. The upper pressing member has a plain metal pressing surface, while the lower pressing member is padded in any suitable 90 manner, as before stated. The shirt to be pressed may be moistened or not, as desired. Usually the shirt has already absorbed sufficient moisture from the atmosphere to enable it to be pressed, but it may be damped 95 with water or moistened by a supply of steam discharged thereon in a well known manner. When the pressing members are advanced toward each other, the pressing plate or form and the holding plate, when 100 it is used, are crushed down upon the shirt and pressure is applied thereto, so as to press the same. The exposed portions of the collar lying above the pressing plate or form are pressed between said plate and the overlying holding plate, but without the production of any imprint of the collar upon the adjacent body portions of the shirt. The padding on the lower pressing member is preferably so arranged as to yield sufficiently 105 to avoid injury to the shirt buttons.

It will, of course, be understood that each pressing machine is provided with a complete outfit of pressing forms or plates 25, cut and proportioned for various sizes of 110 shirt. Several such plates or forms are provided for each size, so that one shirt can be arranged on one pressing member while another shirt is being pressed on the other. The same holding plate will serve for various 115 sizes of shirts.

The apparatus described enables shirts to be arranged in symmetrical form and position and so held while pressing, and not only avoids unsightly wrinkles and folds in the 120 garment, but also prevents leaving an imprint of the collar upon the shirt. It thereby enhances the appearance and value of the shirt and enables increased prices to be secured therefor. It can be manipulated by 125 130

unskilled operators and may be applied to any form of pressing machine.

What I claim is:—

1. A garment pressing machine, comprising upper and lower relatively movable pressing members, and a pressing plate or form upon which the garment is arranged, said plate or form having a recess in one end with substantially straight diverging edges for receiving and holding the collar during the pressing operation and at the same time stretching the folded side edges of said collar at the neckband into abnormal form to form a V shaped straight sided neck opening in the collar. 10
2. A garment pressing machine, comprising upper and lower relatively movable pressing members, a pressing plate or form upon which the garment is arranged, said plate or form having a recess in one end with substantially straight diverging edges for receiving and holding the collar during the pressing operation, and a holding plate lying above said pressing plate or form holding the garment collar down upon the same, and means for yieldingly pressing said holding plate down upon the garment when said pressing members are out of co-operative pressing relation. 20
3. A garment pressing machine, comprising upper and lower relatively movable pressing members, collar holding means adapted to be moved to a position over the collar of a garment on said lower member, and means for advancing said holding means bodily along the collar. 30
4. A shirt pressing machine, comprising upper and lower relatively movable pressing members, a coöperating plate therefor having a shirt collar engaging portion of approximately the same shape and size as the collar, said plate being movably mounted upon the lower pressing member and movable into and out of a position in which the lower holding portion thereof lies over the collar of a shirt on the lower pressing member. 40
5. A shirt pressing machine, comprising upper and lower relatively movable pressing members, a coöperating plate therefor having a shirt collar engaging portion of approximately the same shape and size as the collar, said plate being movably mounted upon the lower pressing member and movable into and out of a position in which the lower holding portion thereof lies over the collar of a shirt on the lower pressing member, and means for moving said plate when in position over the collar in a plane parallel with the face of the lower pressing member. 50
6. A shirt pressing machine, comprising upper and lower relatively movable pressing members, a coöperating plate therefor having a shirt collar engaging portion of approximately the same shape and size as the

collar, said plate being movably mounted upon the lower pressing member and movable into and out of a position in which the lower holding portion thereof lies over the collar of a shirt on the lower pressing member, means for moving said plate when in position over the collar in a plane parallel with the face of the lower pressing member, and means for yieldingly pressing said plate down upon the shirt collar when said pressing members are out of coöperating pressing relation. 70

7. A garment pressing machine, comprising upper and lower relatively movable pressing members, and a plate hinged to said lower member and arranged to swing to a position over the same for holding the garment in pressing position, and means permitting said plate to slide over the garment in a plane parallel with the faces of the 85 pressing members.

8. A garment pressing machine, comprising upper and lower relatively movable pressing members, a plate hinged to said lower member and arranged to swing to a position over the same for holding the garment in pressing position, and a spring for pressing said plate yieldingly upon the garment while said pressing members are out of coöperating pressing relation. 90

9. A garment pressing machine, comprising upper and lower relatively movable pressing members, a plate, supporting means therefor arranged to permit said plate to swing to a position over the said lower member for holding the garment in pressing position, and also to have sliding movement over the garment, and a spring for pressing said plate yieldingly upon the garment while said pressing members are out of co-operative pressing relation. 100

10. A garment pressing machine, comprising upper and lower relatively movable pressing members, a presser plate or form upon which the garment is arranged, said plate having a recess in one end with approximately straight diverging edges for receiving and holding the collar during the pressing operation, and a holding plate supporting means therefor arranged to permit said plate to swing to a position over the pressing plate or form for holding the garment collar in pressing position, and also to have sliding movement over the garment. 110

11. A garment pressing machine, comprising upper and lower relatively movable pressing members, a pressing plate or form upon which the garment is arranged, said plate or form having a recess in one end with substantially straight diverging edges 115 for receiving and shaping the collar during the pressing operation and at the same time stretching the folded side edges of said collar at the neckband to form a V shaped neck opening with straight sides, and means 120

125

lying above the collar for holding it down upon said plate while said pressing members are out of coöperating pressing relation.

12. In a garment pressing machine, a
5 pressing plate or form upon which the garment is arranged, said plate or form having a recess in one end with substantially straight diverging edges for receiving and

shaping the collar during the pressing operation and at the same time stretching the 10 folded side edges of said collar at the neckband to form a V-shaped neck opening with straight sides.

In testimony whereof I affix my signature.

BLUFORD W. BROCKETT.
